ALBERT HENRY MIDGLEY, OF ACTON VALE, ENGLAND, ASSIGNOR OF ONE-HALF TO C. A. VANDERVELL & COMPANY LIMITED, OF ACTON VALE, ENGLAND.

IGNITION SYSTEM FOR INTERNAL-COMBUSTION ENGINES.

1,324,430.

Specification of Letters Patent.

Patented Dec. 9, 1919.

Application filed April 1, 1919. Serial No. 286,655.

To all whom it may concern:

Be it known that I, ALBERT HENRY MIDGLEY, a subject of the King of Great Britain and Ireland, and residing at Warple Way, 5 Acton Vale, in the county of Middlesex, England, have invented certain new and useful Improvements in and Relating to Ignition Systems for Internal-Combustion Engines, of which the following is a specification.

This invention relates to an improved ignition system for internal combustion engines and more particularly to the electrical connections between the ignition apparatus and dynamo on the one hand, and the switchboard and battery on the other hand, the invention being more especially intended for use in ignition arrangements of the character described in British specifications 20 Nos. 9282 and 9740 of 1918, although not limited thereto.

The main object of the invention is to reduce the connections referred to, to a minimum, at the same time insuring the running of the engine, even when all wires are broken, as may for instance happen, when the switchboard on an aircraft is hit by enemy firing.

Another object of the invention is to insure flexibility of control of the ignition system without increasing the number of the connections.

One feature of the invention consists in temporarily short-circuiting the contact breaker, *e. g.*, by earthing and preferably, but not necessarily, through a resistance in order to reduce the rate of change of current through the primary of the induction coil to such an extent as to prevent the induction in the secondary being sufficiently high to produce sparking.

Another feature of the invention consists in the use of a two-way switch for effecting the short-circuit hereinbefore referred to, 45 of either the one or the other of two contact-breakers associated with two ignition sets respectively in order to put either the one or the other out of action.

A further feature of the invention consists in connecting the connecting wire between the dynamo and the ignition coil or coils to one or the other of two earthed batteries by means of a two-way switch, in order to be able to utilize either the one or the other battery.

Referring to the accompanying drawing which illustrates the invention diagrammatically and by way of example, *a*¹, *a*² are two distributors associated with two banks of cylinders, *b*¹, *c*¹ the primary and secondary coil of the ignition coil, and *d*¹, *e*¹ the cam and earthed make and break of the circuit breaker associated with one bank of cylinders, and *b*², *c*² the primary and secondary coil of the ignition coil, and *d*², *e*² the cam and earthed make and break of the circuit breaker associated with the other bank of cylinders.

*D*¹, *D*² are two points of connections of the two circuit breakers, respectively, which are connected to the stationary contacts of a switch *S* through which the one or the other circuit breaker is short-circuited by earthing, preferably through a resistance *R*, in order to put either the one or the other set of ignition out of action, by reducing the rate of change of current through the primary of the respective induction coil to such an extent as to prevent the induction in the secondary being sufficiently high to produce sparking. An additional resistance *r*¹, *r*² is preferably inserted between the points of connection *D*¹, *D*² of the circuit breakers and the primary *b*¹, *b*² of the respective induction coils.

f is the dynamo which supplies the necessary current for the ignition coils, and which is provided with three brushes, the two brushes of which *g*¹, *g*² are earthed, while its other brush *g*³ is connected to the ignition system by the connecting wire *h*. The dynamo, which in the diagram is shown as a four-pole machine, is provided with a shunt winding *i*, one end of which is connected to the point of connection *j* between the dynamo and the ignition system, while its other end is earthed at *g*². The automatic cut-out *k* is inserted between the point of connection *j* and the brush *g*³.

The connecting wire *h* between the dynamo and the ignition coils is connected to one or the other of two earthed batteries *l*¹, *l*² by means of a two-way switch *m*, in order to be able to utilize either the one or the other battery. *A* is an ammeter inserted in the latter circuit.

Each of the ignition coils is preferably provided with a trembler *n*¹, *n*², respectively, joined together at the point of connection *N* and controlled by the closing of an

5 earthed switch σ , being rendered operative when the corresponding makes and breaks e^1, e^2 are open. B^1, B^2 are two earthed condensers associated with the respective tremblers of the ignition coils.

10 The ignition set or sets and the dynamo form a compact unit of construction which is connected to the batteries, one of which is capable of being used as an emergency battery, and to the various switches and instruments on the switch-board by means of a limited number of connections, the latter being such that even if they are completely destroyed, the ignition set or sets are still capable of being operated straight from the 15 dynamo.

What I claim is:—

1. An ignition system for internal combustion engines, comprising a source of cur-

rent, an ignition coil having a primary and 20 a secondary winding, a contact breaker and means for short-circuiting the contact-breaker, said means comprising a switch and a resistance in series therewith, as set forth.

2. An ignition system for internal combustion engines, comprising a source of current, two ignition coils having primary and secondary windings, two contact breakers connected with the respective primary windings of the ignition coils and means capable of short-circuiting the one or the other contact-breaker, as and for the purpose set forth.

25 In testimony whereof I have signed my name to this specification.

ALBERT HENRY MIDGLEY.
